UNITED STATES PATENT OFFICE.

FREDERICK C. STREB AND ELMER AYER, OF ROCHESTER, NEW YORK.

TYPE-BAR CARRIER.

Application filed March 5, 1927. Serial No. 173,153.

The object of this invention is to provide an individual type bar carrier for multigraph or other similar machines by means of which a name, address or legend may be 5 printed in any desired position on an otherwise finished sheet and this address or legend quickly changed on each sheet fed thru the multigraph.

This and other objects of this invention 10 will be fully illustrated in the drawing, described in the specification, and pointed out in the claims at the end thereof.

In the accompanying drawing:

Figure 1 is a transverse sectional view of 15 the printing drum, the inking rolls and platen of a multigraph with the individual type bar carrier mounted on the printing drum ready for printing.

Figure 2 is a detail perspective view of the 20 individual type bar carrier.

Figure 3 is a detail sectional view of the 25 type bar carrier.

In the several figures of the drawing like 30 reference numerals indicate like parts.

For advertising purposes it is often 35 desirable to imprint on each of a number of otherwise finished sheets an individual name, address or legend. In order to do this either a high priced printing machine designed to 40 produce this type of work must be used, or the imprint to be added must be made practically by hand. The type bar carrier forming the subject matter of this invention makes it possible, however, to perform this 45 type of work on the ordinary multigraph, or other similar machine, and while it may not do it quite rapidly as is possible with the machine designed for this type of work, the work is done as well in the multigraph with 50 the aid of the type bar carrier, and far better and faster than is possible with a manual or semi-manual method.

In Figure 1 we have illustrated in section 55 a printing drum of a multigraph or other similar machine and its associated parts with the individual type bar carrier mounted on the printing drum. This type drum is indicated by reference numeral 1 and is mounted on a shaft 2. The type drum 1 is provided near its periphery with two transverse rods 3 and 4 that are ordinarily used for supporting the type on the drum and locking it in place thereon. The individual type bar carrier is supported and adjusted between the 60 supporting shaft 2 and the bars 3 and 4 as will presently appear.

The type bar carrier proper in the form illustrated in Figures 2 and 3 comprises three plates 5, 6 and 7. Plates 7 and 5 form the front and back of the type bar carrier and are of the same height and are beveled at the bottom to form the angular sides of an inverted trough or channel in the bottom of the type bar carrier. The bottom of the center plate 6 provides the base of this inverted 65 channel and for this reason does not extend flush with the bottom of the ends of the plates at either side thereof. The center plate 6 also extends only part way to the top of the type carrier so that the top edge of 70 the center plate forms the bottom of the type bar receiving channel of which the sides are formed by the upper ends of the front and back plates 7 and 5 respectively.

The back plate 5 is fastened to the center 75 plate by means of the screws 8 and 9 which pass thru suitable holes in the back plate and are threaded into the center plate 6. The front plate 7 is fastened to the center plate by means the screw 10, which passes 80 thru a suitable hole in the front plate 7, and is also threaded into the center plate.

On the back plate 5 are carried the guide 85 lugs 11 and 12. These lugs are suitably fastened to the plate by means of a screw at the top and bottom thereof. In each of the guide lugs is provided an angular groove 13 into which the bar 4 of the type drum is adapted to engage. The type bar carrier is mounted on the type drum by first sliding 90 the guide lugs 11 and 12 in engagement with the bar 4 of the type drum until this bar rests solidly in the bottom of the angular 95 grooves 13 in each of these guide lugs. The bottom of the type bar carrier is then sprung 100 in place over the supporting shaft so that the inverted channel thereof straddles a portion of the perimeter of the shaft. In order to brace the type bar carrier to steady it and hold it in a radial position in the type drum 105 the carrier is provided with an adjusting screw 14. The screw passes thru the type bar carrier being threaded in the plates 5 and 6 and passing thru a reamed hole in the plate 7. The screw 14 projects from the back 110 of the type bar carrier and is adjusted therein until the end of this screw rests firmly against the periphery of the bar 3 as illustrated in Figure 1.

The type bar carrier is clamped in place 115 against endwise movement by the clamping screws 15 and 16 that are threaded into the

guide lugs 11 and 12 respectively. The clamping screws are conical at the outer ends and project into the angular groove 13 of the guide lugs. After the type bar carrier is 5 properly placed on the type drum and the bar 4 is located in the guide grooves, the clamping screws are threaded into the guide lugs until their conical ends engage the periphery of the rod 4 and force this bar in 10 place into the angular grooves of the guide lugs until the bar is firmly clamped in place therein.

After the type bar carrier has been mounted on the type drum as described and 15 illustrated it is ready to receive the type slug 17 containing the type of the name, address or legend to be printed by means of the type carrier. This type slug is preferably cast in a single piece with a linotype machine 20 or other machine, but may be a line of individual types properly held together so that it can be handled and placed into the type bar carrier. The channel formed in the top of the type carrier has a width that 25 is slightly smaller than the width of one of the type slugs that is to be inserted therein. In inserting the slug, the upper ends of the plates 5 and 7 forming the sides of the channel are therefore slightly spread apart 30 so that after the type slug is place in the channel sufficient tension is placed against the side of the type slug by the yielding sides of the channel that will hold the type slug in place in the type bar carrier.

35 For the purpose of holding the type slug in a predetermined position in the type bar carrier, a lug 20 is provided at one end of one of the plates. This lug slightly projects across the end of the channel so that it forms 40 a stop for any type slug that is inserted into the channel. The fact that the plates 5 and 7 are attached to the center plate 6 near their lower ends makes it possible for them to slightly yield when forced apart at 45 the top and it is the yielding pressure of these plates and the lug at the end of the channel that holds the type slug in the proper position on top of the type carrier.

After the type slug is inserted in the carrier the type drum is turned in a counter-clockwise direction until the type has been 50 brought in contact with one or both of the ink rollers 21 and 22. The type is thus inked and is then moved back in a clockwise direction in a complete revolution of the 55 type drum during which the inked type is impressed on the sheet fed thru the multigraph while passing the platen roller 23. At the end of the revolution the type slug 60 is pulled out of the channel in the type carrier and a new one inserted in its place so that a repetition of the operation of the multigraph as above set forth will produce another printed impression by the new type slug on the next sheet fed thru the machine.

A paper shim may be placed between the front plate 7 and the center plate 6 in order to slightly increase the width of the receiving channel of the type bar carrier in order to adjust the width of the channel to correspond to the thickness of the type slug to be inserted therein. For larger size type slugs the width of the receiving channel is increased by the use of a thicker center plate 6. 75

We claim:

1. A type bar carrier for printing drums of multigraphs having a central supporting shaft, comprising a supporting member, an inverted channel formed at the bottom of 80 said supporting member and adapted to straddle a portion of the perimeter of said central supporting shaft, a channel at the top of said supporting member, a yielding side provided on said channel adapted to 85 yieldingly hold a type slug in place in said channel, means for locking said supporting member in place in said type drum.

2. A type bar carrier for printing drums of multigraphs having a central supporting shaft and a pair of spacing bars, comprising a supporting member, an inverted channel at the bottom of said supporting member, a channel at the top of said supporting member, a clamping member carried by said supporting member and adapted to engage one of said spacing bars, a bracing member carried by said supporting member and adapted to engage the other of said spacing bars to hold said supporting member in a radial position in said printing drum. 95

3. A type bar carrier for printing drums of multigraphs having a central supporting shaft and a pair of spacing bars, comprising a pair of plates having their opposing bottom edges beveled, a third plate between said pair of plates and having its bottom located to form the bottom of an inverted channel with the beveled bottom edges of said pair of outer plates, the upper ends of said pair of outer plates projecting above the top of said center plate and forming a channel at the top of said supporting type bar carrier, a guide lug on one side of one of said plates, an angular groove formed in said guide lug adapted to receive one of said pair of spacing bars, a clamping bolt threaded into said guide lug and projecting into said angular groove in front of said spacing bar located in said groove for locking said spacing bar in place in said groove, an adjustable bracing member projecting from one of said outer plates and adapted to engage the other of said spacing bars to hold said type bar carrier in a radial position in said type drum. 110

4. A type bar carrier for printing drums of multigraphs having a central supporting shaft and spacing bar spacing the ends of the drum near the periphery thereof, said carrier comprising a supporting member 115

adapted to rest with its bottom edge on the periphery of the central supporting shaft, clamping means provided on the side of said supporting member and adapted to engage said spacing bar to hold said supporting member projecting radially from the periphery of said supporting shaft.

5. A type bar carrier for printing drums of multigraphs having a central supporting shaft and spacing bar spacing the ends of the drum near the periphery thereof, said carrier comprising a supporting member adapted to rest with its bottom edge on the periphery of the central supporting shaft, clamping

means provided on the side of said supporting member and adapted to engage said spacing bar to hold said supporting member projecting radially from the periphery of said supporting shaft, an adjusting member on the side of said supporting member and adapted to engage another of said spacing bars to brace said supporting member from the spacing bar. 15

20 In testimony whereof we affix our signatures.

FREDERICK C. STREB.
ELMER AYER.
